DISPLAY STAND

John Calvin Wagner and Alfred J. Engel, Baltimore, Md., assignors to The Eastern Box Company, Baltimore, Md., a corporation of Maryland

Application December 16, 1935, Serial No. 54,764

9 Claims. (Cl. 248—152)

Our invention consists in a new and useful improvement in display stands and is designed more particularly to provide a stand, made from a single blank and folded, for the display of merchandise and particularly boxes, cartons and containers of foodstuffs. Our stand is constructed of any kind of suitable material, such as heavy cardboard, corrugated board, chip board, etc., in a stamped-out blank in a single piece, the proper scores and lines of severance being provided, so that the blank may be folded to form the stand. The particularly novel and useful features of our improved stand are the wings on the side panels on either side of the article supporting step, to prevent accidental displacement of the article, the flaps from the side panels to afford a foundation for the step, and the flaps from the side panels forming bracing struts for the side panels, thereby giving the stand great strength to carry the load and withstand shocks.

While we have illustrated in the drawings filed herewith and have hereinafter fully described one specific embodiment of our invention, it is to be distinctly understood that we do not consider our invention limited to said specific embodiment, but refer for its scope to the claims appended hereto.

In the drawings:

Fig. 1 is a perspective view of our improved stand, with a receptacle indicated in dotted lines 30 in position upon the stand.

Fig. 2 is a vertical section on the line 2—2 of Fig. 3.

Fig. 3 is a vertical section on the line 3—3 of Fig. 2.

Fig. 4 is a horizontal section on the line 4—4 of Fig. 3.

Fig. 5 is a vertical section on the line 5—5 of Fig. 2.

Fig. 6 is an enlarged fragmentary perspective view of the over-lapping flaps and locking tongue therefor.

Fig. 7 is a plan view of the unfolded blank.

As illustrated in the drawings, our improved stand is formed from a single blank (Fig. 7) comprising the panels A, B, C, and D, of which A and C are the sides, B the front and D the rear.

From the bottom edge of the blank, scores 1 and 2 extend at right angles to divide the front panel B from the side panels A and C respectively. These scores 1 and 2 extend for approximately one-third of the width of the blank, and lines of severance 4 and 5 are projections of the scores 1 and 2 respectively, to separate the panel B from the panels A and C. A score 6 parallel with the bottom edge of the blank connects the upper ends

of the scores 1 and 2, and a score 7 parallel with the score 6 is disposed on the panel B approximately midway between the score 6 and the top of the panel B. These scores 6 and 7 divide the panel B into the lower portion B—1, the middle portion B—2 and the upper portion B—3. From the upper portion B—3, there extends upwardly the tongue B—4 with a score 7' between the portion B—3 and tongue B—4. The tongue B—4 has the vertical score 8 and horizontal line of severance 9, to form the tab B—5.

The panel A has a score 10 extending downwardly from its upper left corner and disposed at an angle slightly less than 90° to the left edge of the panel A. A score 11 is aligned with the score 10, and an arcuate line of severance 12 connects the adjacent ends of the scores 10 and 11, to form an upwardly extending wing A—1. A line of severance 13 extends at right angles from the lower end of the score 11 to the line of severance 4, to form the flap A—2 which has its outer edge 14 formed parallel with the scores 10 and 11. This flap A—2 is provided with an elongated slot S disposed at right angles to the scores 10 and 11. The panel A also has the score 15 extending downwardly from the point of juncture of the scores 1 and 6, and at right angles to the scores 10 and 11, and the score 16 aligned with the score 15, and a semi-circular line of severance 17 connects the adjacent ends of the scores 15 and 16, to form the wing A—3. Lines of severance 18 extend at right angles from the outer ends of the scores 15 and 16 to the line of severance 13, to form the flap A—4.

The panel C is provided with the scores and lines of severance 10 to 18, similarly to the panel A, to form the wing C—1, the flap C—2, the wing C—3 and the flap C—4. The flap C—2 is provided with the elongated slot S—1.

The panel D is divided from its adjacent panel C by the score 19.

To form our improved stand, the blank is folded on the scores 1 and 2, and 19, at right angles, bringing the left edge of the panel A adjacent the right edge of the panel D. The meeting edges of the panels A and D are then connected by the gummed strip G. The flaps A—2, C—2 are bent downwardly at right angles on the scores 10 and 11, until their outer edges 14 bear against the panels on the opposite sides of the stand. The flaps A—4, C—4 are bent downwardly at right angles on the scores 15 and 16 and the portion B—2 of the panel B is bent rearwardly and downwardly on the score 6 until it rests upon the flaps A—4, C—4, and between the wings A—3, C—3. The

portion B—3 of the panel B having been bent upwardly and rearwardly on the score 7 is positioned so that its upper part rests on the flap C—2. The tongue B—4 having been bent rearwardly on the 5 score 7' is inserted through the slots S—1 and S. The tab B—5 is then bent downwardly on the score 8, thus locking the tongue B—4 and the flaps A—2, C—2, in position.

It is obvious from Fig. 1 that the receptacle R 10 may be positioned upon the portion B—2, forming the supporting step, and between the wings A—1, C—1 and the wings A—3, C—3, and is thus securely supported upon our improved stand. It is also obvious that, if desired, a second receptacle 15 R can be positioned upon the top of the receptacle R and between the upper portions of the wings A—1 and C—1.

Having described our invention, what we claim is:

20 1. A display stand comprising a middle portion forming a supporting platform, and side portions having two sets of inwardly projecting flaps, one set forming supporting abutments for said platform and the other set forming co-acting expanders bearing against the side portions.

25 2. A display stand comprising a middle portion forming a shelf for a supporting platform, and side portions, each of said side portions having an inwardly projecting flap bearing against the 30 other side portion, to form bracing struts.

3. A display stand for supporting an article comprising a middle portion forming a supporting platform, and side portions having upwardly projecting wings forming retaining walls for the article, and inwardly projecting flaps forming supporting abutments for said platform, each side portion having an inwardly projecting flap engaging the other side portion to form bracing struts.

40 4. In a display stand, the combination of a rear wall; two side walls projecting forwardly from said rear wall and provided with inwardly turned flaps, each flap bearing against the opposite side wall; and a front wall having a portion turned rearwardly and downwardly to form a supporting platform, and a portion turned upwardly and disposed upon one of said flaps.

45 5. In a display stand, the combination of a rear wall; two side walls projecting forwardly from said rear wall and provided with inwardly turned flaps, each flap bearing against the opposite side wall; a front wall having a portion turned rearwardly and downwardly to form a supporting platform, and a portion turned upwardly and disposed upon one of said flaps; and a tongue on 50 said upwardly turned portion transfixing both of said flaps.

6. In a blank for a display stand, the combination of a front panel divided into three portions separated by scores; a panel on each side of the front panel, separated from one portion of the front panel by a score and from the other two portions of the front panel by a line of severance, each of said side panels having a flap formed by a pair of aligned scores with an arcuate line of severance between, and a second line of severance from the end of one of the scores. 5

7. In a blank for a display stand, the combination of a front panel divided into three portions separated by scores; a panel on each side of the front panel, separated from one portion of the front panel by a score and from the other two portions of the front panel by a line of severance, each of said side panels having a flap formed by a pair of aligned scores with an arcuate line of severance between, and a second line of severance from the end of one of the scores, the 10 arcuate line of severance forming a wing. 15

8. In a blank for a display stand, the combination of a front panel divided into three portions separated by scores; a panel on each side of the front panel, separated from one portion of the front panel by a score and from the other two portions of the front panel by a line of severance, each of said side panels having a flap formed by a pair of aligned scores with an arcuate line of severance between, and a second line of severance from one end of one of the scores, and each of said side panels having a second flap formed by a pair of aligned scores with a semi-circular line of severance between, and a line of severance from the outer end of each score 30 to the line of severance forming the first mentioned flap. 35

9. In a blank for a display stand, the combination of a front panel divided into three portions separated by scores; a panel on each side of the front panel, separated from one portion of the front panel by a score and from the other two portions of the front panel by a line of severance, each of said side panels having a flap formed by a pair of aligned scores with an arcuate line of severance between, and a second line of severance from one end of one of the scores, and each of said side panels having a second flap formed by a pair of aligned scores with a semi-circular line of severance between, and a line of severance from the outer end of each score 40 to the line of severance forming the first mentioned flap, the arcuate line of severance on each panel forming a wing, and the semi-circular line of severance on each panel forming a wing. 45
